UNITED STATES PATENT OFFICE.

JOSEPH C. O'NEILL, OF TRENTON, NEW JERSEY.

SCULLING DEVICE.

1,357,111.

Specification of Letters Patent. Patented Oct. 26, 1920.

Application filed August 15, 1919. Serial No. 317,771.

To all whom it may concern:

Be it known that I, JOSEPH C. O'NEILL, a citizen of the United States, residing at Trenton, in the county of Mercer and State 5 of New Jersey, have invented new and useful Improvements in Sculling Devices, of which the following is a specification.

The invention relates to boats and more particularly to propelling devices for small 10 crafts and has for an object to provide a simple device for sculling to propel the craft through the water.

The invention comprehends among other 15 features a support for an oar, the support being preferably attached to the stern of a row boat and the like, to position the oar so that a reciprocating movement of the latter will act in the nature of a propeller to force the craft to head through the water. To 20 this end the support is suitably anchored in a socket and the oar is swiveled thereon in a manner which will insure proper operation of the latter to accomplish the desired result.

25 In the further disclosure of the invention, reference is to be had to the accompanying drawings, constituting a part of this specification, in which similar characters of reference denote corresponding parts in all 30 the views, and in which,—

Figure 1—is a rear elevation of the device, the blade end of the oar being cut away to show the stem of the oar in cross section.

35 Fig. 2—is a plan view.

Fig. 3—is a vertical sectional view taken on the line 3—3 in Fig. 1, and

Fig. 4—is a vertical sectional view taken on the line 4—4 in Fig. 2.

40 Referring more particularly to the views, the numeral 10 indicates the stern of a boat, such as a row boat or skiff and the numeral 11, a socket which is suitably attached by screws 12 to the stern of the skiff. The 45 socket proper is of a tapered form to receive a tapered stem 13 formed integral with a support 14, the latter comprising a closed loop 15 having the upper portion 16 thereof of straight and the remaining portion 17 of the loop curved and formed with a beveled surface 18. Midway of the straight portion 16, the support is formed with a longitudinal bored projection 19 through which passes loosely, a swivel element 20, the latter being inserted from the lower end to project up through the projection and re-

ceive a plurality of nuts 21 which support the swivel element in a depending position permitting it to be readily rotated or reciprocated.

A combined clamp and oar holder 22 for an oar 23 is provided to support the oar relative to the loop of the support and consists of a plate 24 formed with notched lugs 25, a band or a strap 26, being arranged to encircle the oar 23 around the stem thereof with the extremities of the band terminating in threaded portions 27 which pass through the notches of the lugs 25 and receive nuts 28. The latter when screwed up on the 70 threaded portion, abut against the faces of the lugs, being adapted to frictionally tighten and secure the band 26 around the oar and thus also rigidly hold the plate 24 to the stem of the oar. One end of the plate 75 24 is formed with a hook 29 which before the plate is clamped tightly upon the oar, is passed through an eyelet 30 formed on the lower end of the swivel element 20 and then when the plate is clamped around the 80 oar by the band 26 in the manner mentioned, a portion of the periphery of the oar will act to form a closed loop 31 in conjunction with the hook 29, thus movably holding the hook in constant engagement with the eyelet 30 and preventing accidental disengagement of one relative to the other.

Referring to Fig. 3, it will be seen that 90 particular care must be taken in the manufacture of the device described so that when the oar is in use, the normal angularity thereof relative to the horizontal, will bring the periphery of a portion of the band 26 into contact with the beveled surface 18 so that these two metallic parts, in sliding frictional contact when the oar is in use, will prevent the wooden portion of the oar from becoming worn out, it being apparent that contact of the wooden portion of the oar with the closed loop, would quickly wear the 100 groove or gouge into the wooden part of the oar and in a very short time render the same unfit for use. Furthermore the art of sculling a boat is one which with the ordinary oar and row lock of the usual design, 105 would not be effectively carried out except by persons who are skilled in the proper manipulation of the oar to accomplish the result. With my form of sculling device, however, it is only necessary to have the 110 handle end of the oar in a reciprocating manner and by an upward pressure, main-

tain frictional contact between the band 26 and the beveled surface 18, thus causing the curvature of the beveled surface to govern the stroke or movement of the blade end of 5 the oar and thus naturally bring about the sculling operation. By providing this form of contact between the metal attachment on 10 the oar and the closed loop, proper operation of the oar is insured and at the end of each stroke, the oar engaging the extremities of the straight cross portion 16, will 15 limit the reciprocating action of the blade end of the oar thus defining the extent of the stroke, it being well known that if the blade end of the oar is carried too far in the sculling stroke, the propulsion of the craft will be materially hampered.

I am aware that various forms of sculling devices have been used heretofore and that 20 the general form of sculling apparatus now generally employed is an ordinary oar with the usual form of U shaped row lock. In this instance the oar tends to jump out of the oar lock, soon becomes 25 worn out at its point of contact with the row lock and the extent of the stroke and the effect of manipulation of the oar to bring about the sculling operation is not defined and therefore the proper manipulation of 30 the oar can not ordinarily be accomplished except by persons who are skilled by long experience in the art of sculling.

With my device it is only necessary to follow the simple direction of reciprocating

the handle end of the oar, maintaining a 35 slight upward pressure thereon and the sculling operation then naturally ensues, the taper of the stem 13 and its coöperating socket 11, being sufficient to maintain proper frictional engagement of the support 14 with 40 the socket.

Having described my invention, I claim—

1. A device of the character described comprising a socket member, a body formed to provide a closed loop and a depending 45 stem with the latter seated in the socket member, the said body and the said loop having a curved portion and a straight portion with the curved portion provided with a beveled surface, and an oar clamp having 50 swiveled depending connection with the straight portion of the body with a portion of the clamp in frictional contact with and adapted to operate over the beveled portion 55 of the body.

2. A device for sculling a boat with an oar comprising a socket member for connection with the boat, a body defining a curved loop and for removable connection with the 60 socket member, said body and said loop having an inclined surface and an oar engaging clamp having a portion thereof operating over the inclined surface of the body to define the stroke of the oar when the latter 65 is actuated.

In testimony whereof I affix my signature.

JOSEPH C. O'NEILL.
